SWINGING DOOR OPERATING MEANS

Fisher G. Dorsey, Houston, Tex.

Application August 28, 1933, Serial No. 687,112

3 Claims. (Cl. 268—66)

My invention relates to means for mechanically opening swinging doors such as are used largely by the public as in the case of car doors or store and office building doors.

It is an object of the invention to provide a means for opening the door, operated from the knob or latch ordinarily provided on doors of this character. I contemplate the connection with the knob or handle for the door of means 10 to mechanically swing the door to open position when the handle or knob is operated.

It is a further object of the invention to provide a simple and effective means for operating the valve which controls the application of pressure fluid to the door-operating means and to so form such mechanism that it will not be affected by the swinging of the door to any normal open position.

It is a further object to combine with the door control device a latching mechanism which tends to latch the door in closed position.

The invention consists in the particular structure of the apparatus controlled from the handle of the door so as to assist the operator in swinging the door when the latch is released. The 25 particular construction of this mechanism may be varied in different ways coming within the scope of the invention, as will be seen from the specification and drawings herewith.

In the drawings Fig. 1 is a broken front elevation of a door showing the application thereto of one form of my invention.

Fig. 2 is a broken detail of the valve operating means shown in Fig. 1.

Fig. 3 is a top view shown in section on the line 3—3 of Fig. 2.

Fig. 4 is a vertical section through the latching mechanism shown in Fig. 1.

Fig. 5 is a broken front elevation of a connection with the knob or latch, different from that shown in Fig. 1.

Fig. 6 is a view illustrating the connection of the knob or handle with the valve operating device shown in Fig. 5, the view being in vertical section through the operating mechanism.

Fig. 7 is a horizontal sectional view through the latching mechanism shown in Fig. 6.

Fig. 8 is a broken view illustrating a different embodiment of the valve operating means.

Fig. 9 is a transverse section on the plane 9—9 of Fig. 8.

Fig. 10 is a side elevation of the rod supporting eyelet taken approximately on the lines 10—10 of Fig. 8.

Fig. 11 is a broken front elevation similar to

Fig. 1 but illustrating a different connection between the operating rod and the control valve.

Fig. 12 is a still different embodiment of a rod actuating means for the control of the valve.

In the embodiment disclosed in Figs. 1 to 4, inclusive, I have shown a door 1 mounted in the frame 2, and pivoted to swing upon hinges 3. The door is provided with a knob or handle 4, which acts to control the latch 5 through the yoke 6. The knob or handle is connected with a squared shaft 7 rotatable in the housing 8 and having connected therewith a plate 9, the ends of which project laterally therefrom and engage with shoulders indicated at 10 on the yoke. It will be seen that when the shaft 7 is rotated in either direction, one of the ends of the plate 9 will engage against one of the shoulders 10 and move the yoke to the left of its position shown in Fig. 4, thus releasing the latch 5.

Secured to the yoke 6 at the inner end of the latch member is a plate 11 which has secured thereto a rod 12, said rod projecting through the side of the housing 8 away from the latch and transversely across the door. It is supported on the door by eyelets 13.

At a point in longitudinal alignment with the hinges 3 of the door is mounted a cam disc 14. Said disc is mounted upon an outwardly projecting arm 15 upon a pin 16 extending in an upright position parallel with the line of the hinges, it being supported upon the door by a plate 17. The disc 14 is approximately circular except on its upper side where it is flattened off at 18. The rod 12 is connected to the disc 14 by means of a link 19 pivotally attached to the disc through a wrist pin 20. Said wrist pin is mounted above the center about which the disc is rotatable and serves to rotate the disc in an obvious manner.

Bearing against the flattened cam surface of the disc 14 is a ball 21 fitted with a socket 22 on the lower end of a rod 23, which extends directly upward parallel with the inner edge of the door and having at its upper end a laterally inclined arm 24 which bears against the head 25 upon a valve stem 26.

The door operating mechanism which has been shown is not a specific part of the invention. I have shown a cylinder 27 housing a piston secured to a piston rod 28 projecting from the cylinder and slideable in brackets 29 on the upper frame of the door. To this rod is secured, by means of a clamp 30, a link 31 which is connected at the other end to a rod 32 fixed upon the upper end of the door. The air or steam which forces the piston longitudinally of the cylinder to move

the door to open position is directed into said cylinder through a pipe 32 which extends into the housing 33. The passage through the housing is controlled by the valve 34 operated by the raising of the stem 25 to allow the passage of steam from the pipe 35 through the housing to the pipe 32. The valve is held in its seat by a spring 36 upon the valve stem and between the housing and the head 24 thereon.

10 It will be obvious that when the knob or handle 4 upon the door is rotated in the usual manner to release the latch 5 of the door, the rod 12 will be moved to the left in the position shown in Fig. 1 so as to rotate the cam disc 13 and elevate the rod 22. This will move the control valve 34 from its seat and allow the passage of steam or air to the cylinder 26 so as to move the piston and mechanically open the door.

In this manner heavy doors which can not be easily manipulated by the ordinary user of the door will be moved to open position with very little effort whatever on the part of the operator. It will be seen that the operating disc 13 is mounted to swing with the door and is spaced outwardly 25 from the door so that when the door is swung to open position the upper surface of the disc 13 will remain in contact with the lower end of the rod 22 in any position of the door. This is because of the fact that the lower contacting member 29 upon the rod is positioned in a line parallel with that of the door hinge as will be clearly apparent from the drawings.

In Figs. 5, 6, and 7 is shown a different embodiment of the connection between the operating rod 12' and the knob 4. In this case there is mounted upon the shaft 7 of the door knob a ratchet wheel 37. On each side of said wheel transversely of the door are opposed racks 38, which are slidably transversely of the door in brackets 39. The ends of the racks 38 project through the side wall of the housing and have on their extending ends thereof the knobs 40. The extending ends project through a plate 41 mounted on the end of the shaft 12'. In this construction it will be seen that when the knob 7 is rotated in either direction it will exert an inward pull upon one of the racks and an outwardly thrust upon the other. The inward pull will engage the head 40 of the rack with the plate 41 and move it to the right of the position shown in Fig. 5. The rack member which moves in the opposite direction will have no effect whatever upon the plate 41 to move the same.

The rod 12' is connected to the similar rod 12'' by means of a lever 42 pivoted upon the door at 43. This connection between the rods 12 and 12'' enables a lateral pull upon the rod 12' to be converted into a thrust in the opposite direction upon the rod 12''. This means of operating the mechanism for controlling the valve is to be used with any particular operating mechanism between the same and the valve.

In Figs. 8 and 9 I have shown a different embodiment of the means for operating the valve control rod 22'. In these views I have shown the transverse rod 12 upon the door as connected to a toggle composed of an upper link 44 and a lower link 45, both of which are connected at 46 to the rod 12. The lower link 45 is supported upon a pin 47 supported in a bracket 48 in a position parallel with the hinges of the door. The lower end of the link 45 is therefore held against longitudinal movement and the upper end of the link 44 is connected pivotally to the rod 22' which extends upwardly parallel with the hinge of the

door for contact with the valve stem 25 of the control valve. In this particular construction, when the rod 12 upon the door is moved to the left in Fig. 8 it will exert an upward thrust upon the control rod 22', so as to open the valve 34 in the manner previously noted. As will be seen from Fig. 10, the eyelet 49 which supports the rod 12 in this embodiment is elongated vertically so as to allow an upward movement of the rod 12 when the toggle is moved to straightened position.

Both of the embodiments disclosed are operated by a thrust upon the rod 12. In Fig. 11 I have shown the control valve as operated through a flexible cable 50. This is accomplished by connecting a rod 12''' through the lever 42 to the cable 50. At a point closely adjacent the inner edge of the door is mounted upon a pin 51, a pulley 52 around which the cable is passed. The periphery of the pulley has its outer side in alignment with the hinge of the door and allows the cable to pass directly upwardly parallel with the door hinge 3 to an eyelet 53 mounted upon a bracket 54 secured to the frame of the door. The cable then is directed laterally for connection to an eyelet 55 at the lower end of the valve stem 25 having thereon a valve 34'. This valve is held upwardly into its seat by means of the spring 36.

The operation of this modification is believed to be clear. The rod 12''' may be connected to the control knob by means such as is disclosed in Fig. 4 and when the said knob is operated a pull will be exerted upon the cable 50 which will open the valve and allow the passage of the pressure fluid to the cylinder 26. The position of the cable adjacent the hinged side of the door is such that it will not be affected by the swinging of the door in its movement to open position.

In Fig. 12 I have shown how the valve rod can be actuated from an operating rod 56, such as is sometimes employed on large doors. In this case the U-shaped rod 56 is pivoted at each end within an eyelet or bracket 57 in the outer side of the door. At the end of the rod 56, adjacent the hinge of the door, is a threaded bolt or shaft 58 which is rotated by the swinging of the operating rod 56 about its pivot in the bracket 57. Mounted upon the shaft 58 is a hollow nut 59 engaged with the threaded surface of the shaft 58 and movable longitudinally through the rotation of said shaft. Upon the inner side of said nut is a laterally extending pin 60, which engages within the slot 61 in the door to prevent rotation of the nut and yet allow a longitudinal sliding movement of the nut along the door. The outer end of the nut 59 is rounded to engage with the lower end of the rod 62 through which the valve may be moved. In this device it will be obvious that when the operating rod 56 is swung downwardly the nut 59 will be moved laterally against the lower end of the rod 62 to exert a thrust thereon and thus enable the operator to control the movement of the valve.

In all of the different embodiments of the invention it will be apparent that the movement of the knob or handle upon the door so as to release the latch in the usual manner will also control the mechanism which opens the door. This makes it particularly adaptable for use in public places where the doors are heavy and hard to operate quickly. The operator by simply engaging the knob and rotating it to release the latch will automatically swing the door to open position through the simultaneous operation of the 75

valve control mechanism. Each arrangement for controlling the valve is so aligned parallel with the hinge side of the door that it will operate with equal effectiveness in any position of the door.

5 The device is simple to operate and may be adapted for use upon any ordinary type of swinging door.

What is claimed as new is:

1. A door frame, a door hinged to swing there-
10 in, a pair of toggle links pivoted on an axis
aligned with the hinged edge of said door, a ver-
tically extending push rod on said frame connect-
ing with one of said links, a door knob, a bolt con-
15 nected therewith, and a rod transversely of said
door connecting said knob and said links, whereby
the rotation of said knob will withdraw said
bolt and move said push rod.

2. A door frame, a door hinged to swing there-
in, a knob on said door, a shaft operatively con-

nected with said knob, a pinion on said shaft, a
pair of parallel racks engaging said pinion, a
yoke having openings to slidably receive the ends
of said racks, enlarged ends on said racks to en-
gage said yoke when said shaft is rotated in 5
either direction, a rod on said yoke and a control
mechanism actuated through a pull exerted on
said rod by one of said racks.

3. A door frame, a door hinged to swing upon
a pivot at one side thereof, a door knob, a longi-
tudinally slidable rod extending from said knob
transversely of said door, means actuated by the
rotation of said knob to move said rod, a push
rod on said frame adjacent to and in approx-
imate longitudinal alignment with said pivot, and 10
means including a pair of toggle levers on said
door actuated by the movement of said trans-
verse rod to exert a push on said push rod.

FISHER G. DORSEY.
